UNITED STATES PATENT OFFICE.

ARTHUR W. WALKER, OF MALDEN, MASSACHUSETTS.

COOKING-STOVE.

SPECIFICATION forming part of Letters Patent No. 605,303, dated June 7, 1898.

Application filed January 7, 1898. Serial No. 665,934. (No model.)

To all whom it may concern:

Be it known that I, ARTHUR W. WALKER, of Malden, county of Middlesex, State of Massachusetts, have invented an Improvement 5 in Cooking-Stoves, of which the following description, in connection with the accompanying drawings, is a specification, like letters and figures on the drawings representing like parts.

10 Prior to this invention most cooking-stoves have been provided with two dampers, one of which opens a direct draft, as when the fire is started, while the other controls the circulation of the products of combustion in the flues of the stove for baking, &c.

I have experimented with and have produced a stove wherein one and the same damper not only controls the direct draft, but also the baking-draft.

20 Figure 1, in top view, shows a cooking-stove containing my improvement, part of the top being broken out to show the interior construction. Fig. 2 is an enlarged sectional detail in the dotted line x , Fig. 1; Fig. 3, a 25 partial section in the dotted line x' , Fig. 2. Fig. 4 shows the damper detached. Fig. 5 shows the damper-actuator; and Fig. 6, an enlarged detail of the meeting ends of the damper-actuator.

30 The stove-body A, having the box-like extension A', constituting a flue A², and the stove-top B, extended at B' to cover said box, said top having a collar B², on which is fitted the smoke-pipe B³, and having suitable 35 covers B⁴, and the top oven-plate C, having between it and the under side of the stove-top walls c' c² to constitute flues to direct the heat from the fire-box along the side of the wall c' in the direction of the arrow 2 into the 40 half of the flue-space d under the oven and thence into the space c³ into the flue-space A², are and may be all as usual. The flue-space A² has at its left-hand side, viewing Fig. 3, a wall e, provided with a direct-draft opening e' and a baking-draft opening e², the 45 two openings being separated by the curved wall c². The wall e is inclined somewhat from a perpendicular, and at the bottom of said wall, at its side next the flue-space A², there is a guideway 2 (see Fig. 3) to receive the lower flaring edge or foot 3 of the damper f, it having, as shown, a lug 4, said damper,

owing to the inclination of said wall e, lying against said wall by a force due to the gravity of the damper, thus making a close joint, 55 and at the same time the foot entering said groove 2 enables the side of said wall to constitute a guide for the damper in all its movements. This damper is the only one used, and it is made to coöperate with and normally cover the draft-opening e' and more or less of the baking-draft opening e².

The extension B' of the stove-top is provided with a slot g, and the under side of the top has connected to it by suitable screws g' 65 two guideways g² g³, in which is placed a damper-mover, shown as composed of two slide-bars h h', each having at one end a like finger h² and an ear h³, having a hole 5, said hole receiving the shank of a knob h⁵. These 70 bars h and h' are passed through said slot into said guideways, and then the ears are overlapped with a finger h² at either side of the lug 4 of the damper, and then the shank of the knob is inserted in the holes 5 of the ears, 75 thus connecting the damper-mover together, and thereafter by pushing said damper-mover to the right or left one or the other finger h² becomes the mover for the damper, so that by this loose connection with the damper it 80 may be moved in either direction, as required. The top of the stove near said slot is marked "Bake," "Check," "Kindle," and the knob is shown at "Bake," and in such position the damper uncovers the most 85 of the baking-draft opening, so that the full effect of the heat of the stove may be utilized for baking.

Should the heat be too great for baking, or if it is desired to check the regular draft of 90 the stove, as when it is closed up for the night, it being desired to keep the fire low or over night, then the knob may be moved to the position marked "Check," and in such position the opening e² will be partially closed. 95 If, however, a fire is to be kindled, then the knob is moved fully to the right opposite the word "Kindle," in which position the damper fully opens the direct draft e' and closes the opening e².

100 By controlling the direct draft, the baking-draft, and the check draft by one and the same damper the stove is rendered more simple as to its care and management and there

is less for the girl who runs the stove to learn, and she is not liable to run the stove on wrong principles.

Having fully described my invention, what I claim, and desire to secure by Letters Patent, is—

1. In a stove, a wall interposed in the path of the smoke from the fire to the smoke-pipe and provided with two openings, combined 10 with one damper to substantially cover either or both said openings, substantially as described.

2. In a stove, an inclined partition or wall located in the path of the smoke from the fire 15 to the smoke-pipe, and provided with a direct-draft opening and a baking-draft opening, combined with one damper coöperating with both said openings, substantially as described.

3. In a stove, an inclined partition or wall 20 located in the path of the smoke from the firebox to the smoke-pipe, said wall being provided with a direct-draft opening and a baking-draft opening and having a groove at the base of said partition or wall, combined with 25 a damper, the lower edge of which enters and slides in said groove, said damper resting by its gravity on and being free to slide on said partition or wall, substantially as described.

4. The combination with a stove provided

with a slot for a damper-knob, and a damper 30 located below said slot, of a damper-operator composed of a jointed two-part bar coöperating with said damper to move it and at the same time keep said slot closed, substantially as described.

5. The combination with a stove, of a damper having a lug, combined with a damper-operator made as a sliding bar having two fingers embracing said lug, substantially as described.

6. A stove having a straight longitudinal partition or wall provided with a direct-draft opening and a baking-draft opening arranged side by side, and other walls c' and c^2 to form flues, combined with a damper moving against 45 one side of said partition and means to move it in a straight line to cover or to uncover the direct-draft opening and uncover more or less of the baking-draft opening, substantially as described.

In testimony whereof I have signed my name to this specification in the presence of two subscribing witnesses.

ARTHUR W. WALKER.
